CHARLES A. FRIEDRICH, OF NEW YORK, N. Y.

METHOD OF PRODUCING HIGH VACUUMS IN X-RAY TUBES AND THE LIKE.

1,083,677.

Specification of Letters Patent.

Patented Jan. 6, 1914.

Application filed October 11, 1910, Serial No. 586,443. Renewed May 27, 1913. Serial No. 770,259.

To all whom it may concern:

Be it known that I, CHARLES A. FRIEDRICH, a citizen of the Empire of Germany, and a resident of New York, county and State of New York, have invented certain new and useful Improvements in Methods of Producing High Vacuums in X-Ray Tubes and the like, of which the following is a specification.

10 This invention has reference to a novel method of producing high vacuums in X-ray tubes and the like and pertains also to improved tubes of that type.

The known X-ray and like tubes and the methods heretofore employed for producing high vacuums required in such tubes are deficient. With the aid of the modern Roentgen apparatus it is possible to pass strong currents through the tubes but this involves 20 certain disadvantages and greatly shortens the life of the tube. Furthermore with the former X-ray tubes, X-rays may be produced of but moderate penetrative power and more of the so called soft rays are produced than of the so called hard and penetrative rays because the inherent deficiencies of those tubes permit the passage of the current between the anode and cathode only after the vacuum has been regulated down 30 to a certain height. If this regulation is not effected the current does not pass between the electrodes but discharges along the inner glass walls of the tube and causes irregular fluorescence of the entire glass bulb 35 without producing X-rays. If under those circumstances a stronger current is applied then the tube is usually destroyed because it simply cracks. These deficiencies of the former X-ray tubes find their explanation in 40 the method of their evacuation and in the disadvantageous location and construction of the regulating device.

In order to produce a lastingly high vacuum in an X-ray tube under present conditions when enormously strong currents are sent through the tube during use both the anode and the cathode should be heated to red heat during the evacuation so that all gases contained in the metal are driven out 45 and removed by the air pump. The regulating device should not be on the outside of the tube but should be located within same near the center so that the gases absorbed by

the regulator may be easily liberated for the purpose of forming a passage for the current. 55

The known methods of evacuation have the disadvantage that the same high potential current which produces the X-rays in the finished tube is also used for heating the electrodes during evacuation. The anode may thus be heated to red heat without causing disturbing secondary effects but not the cathode. The cathode acquires but little heat in a low vacuum and only after the 60 cathodic rays become almost invisible it acquires heat quickly. If under those conditions the current is not shut off, large quantities of gas are expelled from the cathode while it acquires a red heat and the current 65 finds an easy way through that gas layer and follows same. This causes that gases as well as volatilized metal vapors are thrown against the glass walls where they form a precipitate in form of a dark ring in the 70 neighborhood of the cathode. A finished tube produced as described exhibits big disturbances around the cathode and such a tube is useless for practical purposes. 75

In the known methods of evacuation the 80 cathode is not heated to red heat because it imperils the tube. As soon as the anode has acquired red heat the current is so reduced that the cathode will not be heated. For this reason current is passed interruptedly 85 through the tube. A tube evacuated in the described manner still contains pretty large quantities of gas in the cathode and as the cathode easily acquires heat in a high vacuum these gases are set free during a continued use of the tube and the above described phenomena take place and the tube 90 becomes useless in a very short time.

Another disadvantage of the use of high potential currents during the process of 95 evacuation is that even at a low vacuum an electrostatic field exists in the tube which reduces to a large extent the efficiency of the air pump. As a consequence of this large quantities of gases which were expelled from 100 the anode and cathode collect in the tube. By the continuous electric discharges and the static field produced thereby these gases as well as volatilized metal vapors are thrown against the glass walls and settle 105 thereon. When the finished tube becomes

cold this fine deposit on the glass walls absorbs part of the gases still contained in the tube and thus forms a fine gaseous layer on the entire inner glass wall. This explains 5 why the current in a completely cooled finished tube passes easier along the glass wall instead of passing between the anode and cathode until the vacuum is regulated down.

In order to prove the existence of this 10 fine gas layer on the inner glass wall reference may be made to a very simple method used years ago before regulating devices on X-ray tubes were known. When at that time a tube did not permit of the passage of the current between the anode and the cathode the tube was simply baked, that is, the tube was subjected to heat in a specially constructed oven. By this heat the gases absorbed by the deposit of metallic vapors on 15 the glass walls were set free and accordingly the vacuum in the interior of the tube was reduced. Care had to be taken that the tube was not appreciably cooled off before current was sent through same otherwise the 20 loose gases would partially be reabsorbed by the metallic deposit on the glass wall and no current for practical purposes would pass. As above mentioned gases and volatilized metal vapor settled on the cooler glass 25 wall and when a high vacuum was produced the static field within the tube prevented quick excavation as required for practical purposes. The pump appears not to be able to draw the residual liberated gases through 30 said static field in a higher vacuum and for this purpose an external regulator has been used. Such regulator consists of prepared asbestos, isinglass, or chemicals possessing a high degree of absorbing gases. After 35 the process of exhaustion the residual gases are absorbed by the deposit on the glass wall and particularly by the prepared mass in the regulator. As a consequence of this the vacuum in the center of the tube is practically 40 an absolute one, in other words the passage of the current between the electrodes is opposed in such a high vacuum by a tremendous electric resistance. For this reason 45 it is easier for the current to find its way along the cooler glass wall where a thin gas 50 layer still is found.

As above mentioned the regulating device on the tubes found in the market is in a disadvantageous location, on the outside 55 and therefore too far away from the center of the vacuum. Such regulator is an encumbrance and necessitates a high auxiliary heating of the regulator mass. Such regulator on a former tube contains asbestos prepared 60 separately before the regulator was fused to the tube and during handling the regulator it reabsorbs some vapors and moisture. Further when fusing the regulator to the X-ray tube water vapors are also formed 65 from the blow pipe and the operator has to

blow into the tube to join the regulator whereby more moisture is absorbed by the prepared asbestos therein. This absorption too has the bad effect of requiring a much longer evacuation. The regulator being outside of the tube causes that the vacuum will be too high between the electrodes for the 70 passage of the current which passage is limited to a certain vacuum. This must be established by means of the regulator before the current will pass between the electrodes. It is however desired to obtain rays of 75 greater penetration, that is, rays which are produced in a still higher vacuum than in the former tubes.

I have produced a novel X-ray tube and devised a novel method of producing a high vacuum therein by means of which high heating of both electrodes in a relatively low vacuum is effected without the use of high 80 potential currents whereby all the deficiencies of the former method, secondary disturbing phenomena are eliminated and the glass walls remain clear and free from deposits. Furthermore there is no static field 85 which prevents the continuous uniform action of the vacuum pump which with the new method can scope easily with the liberating gases from the electrodes in an unobstructed manner. To avoid deposits of 90 metal on the glass wall no high potential currents are passed through the tube during the process of evacuation and the absorbent mass of the regulator is located near the center of the vacuum so that the passage of 95 the current is not opposed by an almost absolute vacuum. The new X-ray tube thus made produces rays of higher penetrative power than those heretofore made.

The peculiar construction of my electrodes 100 renders it possible to heat both the anode and the cathode simultaneously to red heat by means of the common current used for incandescent lamps. The absence of electrical discharges and the static field created 105 thereby allows the pump to work with its full capacity whereby the liberating gases are quickly removed and cannot collect within the tube. Mercury vapors which formerly were produced within the evacuated space by the electrical discharges are 110 accordingly not produced by my novel method and therefore not found in the finished tube.

To make the invention entirely clear reference is made to the accompanying drawing in which an X-ray tube is illustrated 115 of my novel construction and exhausted according to my novel method and in which:

Figure 1 represents in elevation partly in section an X-ray tube embodying in desirable form the present improvements. Fig. 2 is a cross section on line 2-2 of Fig. 1, and Fig. 3 is a modification.

In the drawing *a* represents the glass bulb,

b is a long glass tube for the anode integral with the bulb, *c* is a somewhat wider and shorter glass tube for the cathode also integral with the bulb and *d* is the remaining part or tip of the exhaust tube also sealed to the bulb by fusion. The anode passes through the long narrow tube *b* into the interior of the bulb and the cathode through the wider and shorter tube *c*. A terminal *b*¹ is formed at the top end of the tube *b* closing off same hermetically and a like terminal *c*¹ is formed at the bottom end of the tube *c* which closes off same hermetically. There are also two auxiliary terminals *e* and *f* whose purpose will be explained farther down.

The anode consists of a slotted steel tube *g* which has a longitudinal slot *g*¹ that extends through its greater length. At the end of the slot *g*¹ a lateral slot *g*² is formed. The slots are provided in the steel tube to impart some spring power so that the tube fits into and bears against the inner walls of the glass tube *b*. To the top end portion of the steel tube a metal wire, preferably a copper wire *h* is soldered to which the platinum wire *i* is fused which passes through the solid glass formed at the end of the tube and forms outside the anode terminal *b*¹. In the lower portion of the steel tube *g* there is the anode proper below the lateral slot *g*². The anode *j* is made of metal such as bronze or copper in the usual manner and secured to the steel tube by means of a screw *j*¹. Below the securing screw *j*¹ the steel tube is surrounded by an asbestos mantle *k* which is held in position by a metal ring *l* located on the bottom portion of the asbestos mantle and adapted to be tightened by a screw *m* passing through two side flanges of the ring as shown in detail in Fig. 2. Around the asbestos mantle metal wire is wound preferably platinum wire *n* the one end of which is secured to the screw *j*¹ so that it is in electric contact with the steel tube *g* and the terminal for the anode. The second end of this wire around the asbestos mantle is secured to a short screw *o* which ends on the asbestos and therefore is not in electric contact with the anode *j*. As shown in Fig. 1 a conducting wire *p* leads from the tensioning screw *m* to the auxiliary terminal *e*. In this way a circuit may be established by means of the anode terminal *b*¹ and the auxiliary terminal *e* of which the high resistance metal or platinum wire forms a part and thus the wire *n* on the asbestos mantle may be heated by a low potential current without passing any current through the anode. As above stated street current or the common incandescent lamp current may be used for heating the high resistance wire *n* on the asbestos mantle and as may be seen from Fig. 1 both the asbestos mantle and the high

resistance wire *n* are within the glass bulb near the center of the vacuum in the finished tube.

The cathode which is in the shorter and wider tube *c* opposite the anode consists of an aluminum rod *q* located in a narrow glass tube *r*. The bottom end of the aluminum rod connects with the terminal *c*¹ by means of a platinum wire *s*. The top end of the aluminum rod *q* is screwed into the cathode proper *t*. The cathode likewise is made of metal, cup shaped at the top and forms a thick rod *t*¹ below. The aluminum rod *q* is preferably screwed into the rod portion *t*¹ of the cathode while the glass tube *r* simply extends into an opening in the lower portion of the thick rod *t*¹. The glass tube *r* is fused to the solid glass portion through which the platinum wire *s* passes. Around the thick rod portion *t*¹ of the cathode *t* an asbestos mantle *u* is provided which is secured by means of a metal ring *v* adapted to be tensioned in the same manner as the ring *l* of the anode. High resistance or platinum wire *w* is wound around the asbestos mantle whose top end is secured to a screw *x* and thus in electric contact with the cathode. The bottom end of the platinum wire is secured by means of a short screw *y* to the copper ring *v* which screw ends on the asbestos mantle and therefore is not in electric contact with the cathode. In connection with the ring *v* is a small bar *z* which connects with the auxiliary terminal *f*. Thus a circuit may be established by means of the cathode terminal *c*¹ and the auxiliary terminal *f* of which the high resistance or platinum wire *w* forms part. In this manner the platinum wire *w* may be heated by common street current or the incandescent light current.

Assuming that the tube is in connection with the pump and is gradually exhausted then at a certain stage of the evacuation the platinum wire around the asbestos mantle is heated to incandescence. The asbestos mantle also gets hot and imparts heat to the anode below and after a certain time the anode proper acquires heat and becomes red. Simultaneously the cathode is heated in like manner. The gases contained in the metal of which the anode and cathode are made are gradually expelled and the liberating gases are at once removed by the air pump in an unobstructed manner because there is no static field within the tube. As both electrodes are heated in this manner no gases will be expelled from the finished tube when a high potential current is passed through same. No deposit is formed on the inner glass walls because there are no secondary disturbing phenomena within the tube under these conditions and there is no collection of gases as were retained in former tubes by the static field.

With the described construction of the electrodes in the tube and the novel method of evacuation a greatly improved tube is resulting whose glass walls remain clear from deposits. No gases can be expelled from the electrodes after the tube has been finished but over and above everything X-rays of higher penetrative power may be produced with such tubes.

- 10 When the finished tube made according to my novel method cools off the asbestos mantles naturally cool off too and as they are treated in the usual manner they absorb the residual gases within the bulb whereby an almost absolute vacuum is produced between the electrodes. If it is desired to use the tube current is passed through the platinum wire on the asbestos mantles whereby some gases are expelled right in the interior 20 of the tube and almost in the path of the current. These expelled gases form so to say a conductive bridge for the high potential currents which then are passed through the electrodes proper.
- 25 In order to render the regulating device automatic the size of the platinum wire on the asbestos mantles is so selected that the strength of the current of the Roentgen apparatus is sufficient to heat that wire and thereby the asbestos mantles below same so that gases are expelled for the purpose of establishing a passage for the high potential current between the electrodes.

In Fig. 3 of the drawing a modification 30 of the described device for heating the electrodes by low potential currents is illustrated. In this modified form the high resistance or platinum wire on the asbestos mantle forms a closed circuit in itself and the heating of this wire and thereby the electrode is effected by induction from an outside primary spool of an induction coil C which fits over the glass tube b. The wire n then forms the fine wire of the induction 40 coil and is heated when current is passed through the primary coil C. The platinum wire w on the asbestos mantle u of the cathode may likewise be heated by a suitable primary coil as described in connection with the platinum wire n on the asbestos mantle k of the anode.

I claim as my invention:

1. The method of producing a high vacuum in an X-ray tube which vacuum will remain constant during a single operation consisting in heating to red heat both the anode and the cathode during evacuation by means of low potential currents.

2. The method of producing a high 60 vacuum in an X-ray tube which vacuum will remain constant during a plurality of operations consisting in heating to red heat both the anode and the cathode during evacuation by means of low potential currents.

3. The method of producing a high

vacuum in an X-ray tube which vacuum will remain comparatively permanent consisting in heating to red heat both the anode and the cathode during evacuation in a relatively low vacuum by means of low potential currents.

4. The method of producing a high vacuum in an X-ray tube which vacuum will remain comparatively permanent consisting in heating to a cherry red heat both the anode and the cathode during evacuation in a relatively low vacuum by means of low potential currents, and expelling thereby all gases contained in both the anode and the cathode.

5. The method of producing a high vacuum in an X-ray tube which vacuum will remain comparatively permanent consisting in heating to high heat both the anode and the cathode during evacuation in a relatively low vacuum, expelling thereby all gases from the anode and cathode, and removing said gases as they are set free.

6. The method of producing a high vacuum in an X-ray tube which vacuum will remain comparatively permanent consisting in heating a regulating device on each electrode within the tube near the center of the vacuum in an independent circuit by low potential currents during evacuation in a relatively low vacuum, and expelling thereby the gases from both the anode and cathode.

7. The method of producing a high vacuum in an X-ray tube which vacuum will remain comparatively permanent consisting in heating a regulating device on each electrode within the tube in an independent circuit by low potential currents in a relatively low vacuum, expelling thereby the gases from both the anode and cathode and removing same as they are set free.

8. The method of producing a high vacuum in an X-ray tube which vacuum will remain comparatively permanent and expelling gases from regulators and both the anode and the cathode in one operation consisting in heating a regulator on the anode and one on the cathode within the tube in a relatively low vacuum by means of low potential currents in an independent circuit, expelling thereby gases from the regulator and the anode and the cathode, removing said gases as they are set free until a high vacuum is obtained, allowing the sealed off tube to cool and the residual gases to be absorbed by the cool regulator.

9. The method of expelling gases from the cathode of an X-ray tube and the like during evacuation consisting in heating a regulating device on the cathode by means of low potential currents in an independent circuit in a low vacuum whereby the gases contained in the cathode are gradually expelled.

10. The method of expelling gases simultaneously from both the anode and cathode

of an X-ray tube and the like consisting in heating a regulating device on each of them by low potential currents in separate circuits which are independent from the circuit 5 of the electrodes, heating thereby gradually the anode and the cathode in a relatively low vacuum and expelling the gases contained therein and removing said gases.

11. The method of evacuating and automatically operating an X-ray tube and the like consisting in heating both the anode and the cathode in a low vacuum by means of low potential currents in independent circuits expelling thereby the gases from the 15 anode, cathode and regulators removing same as they are set free until a high vacuum is obtained, allowing the sealed off tube to cool and the residual gases to be absorbed, and expelling the absorbed gases partially 20 by the current of the Roentgen apparatus.

12. An X-ray tube comprising an anode and a cathode, and an electric heater on the anode and one on the cathode within the tube for the purpose of heating the anode 25 and the cathode during manufacture.

13. An X-ray tube comprising an anode and a cathode, an electric heater on the anode in an independent circuit, and an electric heater on the cathode in an independent circuit, both within the globe. 30

14. An X-ray tube comprising a globe with central tubes thereon, an anode having an electric heater near its inner end within the globe, an auxiliary terminal for establishing an independent circuit, a cathode 35 with electric heater near its inner end, and an auxiliary terminal for establishing an independent circuit.

15. An X-ray tube comprising a globe with central tubes thereon, an anode in one tube extending into the globe, a layer of asbestos near its inner end, high resistance wire thereon connecting with one end with the cathode and an auxiliary terminal connecting with the other end of said high resistance wire, a cathode, an asbestos layer near its inner end, high resistance wire on the asbestos connecting with one end with the cathode, an auxiliary terminal connecting with the other end of said high resistance wire so that independent circuits may be established for the purpose of heating the anode and cathode simultaneously but separately by low potential currents. 40 45 50
